UNITED STATES PATENT OFFICE

2,471,218

BAG HOLDER AND RELEASER

Lovic O. Jones, Greenfield, Tenn.

Application October 30, 1947, Serial No. 783,097

8 Claims. (Cl. 248—95)

1

This invention relates to new and useful improvements in bag holders and the primary object of the present invention is to provide a device for holding bags and the like including novel and improved means for selectively releasing the bag from the holder.

Another important object of the present invention is to provide a bag holder and releaser including a plurality of pivotal bag supporting elements that are so designed as to conveniently engage a bag to support the same in an easily accessible position.

A further object of the present invention is to provide a bag holder and releaser including novel and improved means for resetting the release mechanism after the same has been actuated.

A still further aim of the present invention is to provide a bag holder and releaser that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a plan view of the bag holder and releaser constructed in accordance with the present invention;

Figure 2 is an elevational view of the present bag holder and releaser, and with parts thereof broken away and shown in section;

Figure 3 is a longitudinal vertical sectional view taken substantially on the plane of broken section line 3—3 of Figure 1;

Figure 4 is an enlarged vertical sectional view taken substantially on the plane of section line 4—4 of Figure 1; and

Figure 5 is an enlarged transverse vertical sectional view taken substantially on the plane of section line 5—5 of Figure 1.

Referring now to the drawings in detail, wherein for the purpose of illustration, there is disclosed a preferred embodiment of the present invention, the numeral 10 represents an annular open frame or rim having a plurality of circumferentially spaced detents or seats 12, 14, 16 and 18 each of which receives a substantially triangular bag supporting member 20 having a pointed extremity 22.

Removably secured by fasteners 24 and brackets 26 to the inner periphery of the frame 10,

2

is an arcuate tubular guide element 28 that extends through circumferentially aligned apertures 30 and 32 provided in each of the seats 12 and 14. The open ends 34 and 36 of this tubular element 28 terminate and are fitted in apertures 38 and 40 provided in the remaining seats 16 and 18.

Slidably mounted in the tubular element 28 and in sleeves 42 and 44 fixedly secured to the outer periphery of the frame, adjacent the seats 16 and 18, is a flexible wire or tightly coiled spring element 46 which is rigidly secured to the base portion 48 of the bag supporting members 20.

Removably secured to the outer periphery of the frame 10, between the seats 16 and 18, by the use of fasteners 50, are the outturned ends 52 of an outwardly projecting yoke 54. The spaced parallel legs 56 and 58 of this yoke are provided with opposed apertures 60 which engage suitable ball bearings 62 rotatably supporting a shaft 64, the reduced ends 66 and 68 of which project outwardly from the legs 56 and 58 and are rigidly secured by welding or the like to the terminals 70 and 72 of the flexible wire 46. Retaining plates 74 and 76 removably secured by fasteners 78 to the outer face of the legs 56 and 58 bear against the flanged portion 80 of the bearing 62 and prevent outward movement of the bearing 62 relative to the opening 60.

Positioned for rotation between the legs 56 and 58, is a wheel 82 that is fixed upon the shaft 64 by a fastener 84. This wheel supports a fixed arm 86 that is connected to one end of a coil spring 88. The opposite, free end of this coil spring 88 is secured to an ear 90 rigidly carried by one of the legs, for example leg 56. This spring normally retains the wheel in such a position that the bag engaging members will be raised, as shown best in Figures 2 and 4.

Removably secured to a U-shaped frame 91 rigidly carried by the yoke, is a pair of fulcrums 92 that pivotally engage one end 93 of a lever or handle 94. The central reduced portion 95 of this lever 94 is pivoted to the bifurcated end 96 of a locking pin 100 that is slidably mounted in an opening 102 provided in the web portion of member 91 and an opposed opening 104 provided in a guide plate 106 rigidly secured between the legs of member 91.

A coil spring 108 carried by a fixed ear 110 mounted on member 91, is connected to the lever 94 to urge the pin 100 downwardly to bear upon the surface of the wheel 82.

The operation of the device is as follows:

The pin 100 is locked in a recess 112 in the

wheel 82 in such a position that the spring 88 is not in tension, and so that the members 20 will be in a raised position as shown in Figure 4. Potatoes or the like are placed in the bag 114, with the member 20 still raised as the wheel 82 as previously stated, is locked by the pin 100 seated in the recess 112. Upon raising the lever 94, the pin 100 will disengage the recess 112, and the weight of the bag 114 and the articles therein will pivot the members 20 downwardly effecting a rotation of the element 46, a like rotation of the wheel 82, and a releasing of the bag. As the wheel 82 is rotated the pin 100 will engage a recess 116 on the wheel to again lock the wheel 82, but this time the spring 88 is in tension so that when the lever 94 is again raised, the wheel will rotate to its normal position, pin 100 will re-engage the recess 112 and the members 20 will be again raised for reuse of the device.

It should be noted that one arm 118 is rigidly secured to the frame 10 and removably supports a handle 120 for steadyng the device in use, and that a U-shaped hanger 122 having its ends 124 and 126 fixedly secured to the frame is provided with an eye portion 128 for engaging a suitable supporting structure such as a scale book or the like (not shown).

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A bag holder comprising an annular open frame, hanger means carried by said frame for engaging a supporting structure, a tightly coiled spring element rotatably and slidably carried by said frame, a plurality of circumferentially spaced bag supporting members fixed to said element, means acting on said element for normally retaining said members in a raised position for supporting a bag, and means for rotating said element to actuate said members to a lowered position for releasing a bag.

2. A bag holder comprising an annular open frame, hanger means carried by said frame for engaging a supporting structure, a plurality of circumferentially spaced recesses provided in said frame, a bag engaging member pivotally mounted in each of the recesses, means normally retaining said members in a raised position for supporting a bag, and means for simultaneously actuating said members to a lower position for releasing a bag.

3. The combination of claim 2 wherein said bag supporting members include substantially triangular elements pivotally secured at their bases to said frame.

4. The combination of claim 2 wherein said retaining means includes resilient means.

5. A bag holder comprising an annular open frame, hanger means carried by said frame for engaging a supporting structure, a plurality of circumferentially spaced recesses provided in said frame, a bag engaging member pivotally mounted in each of the recesses, a yoke carried by the frame, a wheel journaled for rotation on the yoke, spring means carried by the wheel and connected to the bag supporting members for normally retaining the latter in a raised position, means for locking said wheel in a normal position, and means for releasing said wheel locking means to lower said bag engaging members.

6. A bag holder comprising an annular open frame, hanger means carried by said frame for engaging a supporting structure, a plurality of circumferentially spaced recesses provided in said frame; a bag engaging member pivotally mounted in each of the recesses, a yoke carried by the frame, a wheel journaled for rotation on said yoke, spring means carried by said wheel and connected to each of said bag supporting members, further spring means acting upon said wheel for actuating said members in a lowered position, means for locking said wheel in an adjusted position for retaining said members in a raised position, and means for actuating said locking means.

7. A bag holder comprising a frame, hanger means carried by said frame for engaging a supporting structure, a plurality of spaced seats provided in said frame, a bag engaging member disposed in each of said seats for pivotal movement, a support carried by said frame, a wheel journaled for rotation on said support, resilient means carried by said wheel and connected to each of said bag supporting members, further resilient means acting upon said wheel for actuating said members in a lowered position, means for locking said wheel in an adjusted position for retaining said members in a raised position, and means for actuating said locking means.

8. A bag holder comprising an endless frame, a tightly coiled spring element, means carried by said frame slidably supporting said element, a plurality of bag supporting members fixed to said element, a support carried by said frame, a wheel journaled for rotation on the support and connected to said element for rotating the latter to raise and lower said members, said members being retained in a normally raised position, spring means acting upon said wheel for actuating said members in a lowered position, means for locking said wheel in an adjusted position for retaining said members in a normally raised position, and means controlling said locking means.
